UNITED STATES PATENT OFFICE.

MAX BRECKER, OF BROOKLYN, NEW YORK.

COMBINED BUST AND SKIRT FORM.

Application filed July 18, 1921. Serial No. 485,609.

To all whom it may concern:

Be it known that I, MAX BRECKER, a citizen of the United States, residing at New York city, borough of Brooklyn, in the county of Kings and State of New York, have invented a certain new and useful Combined Bust and Skirt Form, of which the following is a specification.

This invention is a combined bust and skirt form, and, speaking generally, the object of the invention is an article of the class specified which is adapted to be used either as a bust form or skirt form or both forms combined at the same time.

Both skirt forms and bust forms have long been known; e. g., it has been the practice to build bust forms with depending skirt portions, usually constructed from metallic ribs and hoops, so as to provide a full length form over which a dress may be fitted. It has also been common to manufacture bust forms without the depending skirt portion, which bust forms are commonly used, more particularly, for demonstration purposes, when supported upon counters, tables, shelves, etc. It has been the practice to support the full length forms on standards, but the bust forms have usually depended for support upon some extraneous article of furniture. In no case, so far as I am aware, has there been suggested a full length figure which was so organized or constructed as to be capable of use as a bust form, without dismantling the same for the purpose of supporting the bust and skirt portions. The present invention, in its preferred form, embodies a bust form so constructed that when used as such, it may readily be set in upright position on any extraneous support and such bust form, has, associated therewith, a skirt portion preferably of fabric, with which it cooperates, and distending means for normally imparting the desired shape to the skirt portion. In practice, the upper part of the skirt portion is shaped to the desired contour by permanently securing it to the lower portion of the bust form, while the desired shape is imparted to the lower end of the skirt portion by a distending member associated therewith, so that the skirt portion hangs freely from the base of the bust portion when the latter is supported in upright position by a suitable standard associated therewith. The parts are so ar-

ranged and proportioned, however, that when desired, the skirt portion can be collapsed and lifted into the interior of the bust portion and maintained in this concealed position by means of the distending member referred to. Thereafter, the bust portion, with the skirt portion housed therein, may be readily removed from the standard and set on a table or other form of support. The parts may be readily collapsed for shipment by collapsing the supporting standard within the bust form to insure compactness of construction and enable it to be contained within a relatively small crate.

Features of the invention other than those specified will be apparent from the following detailed description and appended claim, read in conjunction with the accompanying drawings.

The accompanying drawings illustrate one practical embodiment of the invention, but the construction therein shown, is to be understood as illustrative, only, and not as defining the limits of the invention.

Figure 1 is a side elevation of the form of the present invention which is a combined bust and skirt form. In this figure the bust and skirt portions are shown in central section in the interest of clearness;

Figure 2 shows the parts collapsed and the device conditioned to function merely as a bust form; and

Figure 3 is a section on the line 3—3 of Fig. 1, showing the lower edge of the skirt portion in elevation.

Referring to the drawings, 1 designates the bust portion of the form which may be constructed of any suitable material and may be economically manufactured of papier-mâché. The bust form 1 is shaped to the human figure and is made hollow in the interest of lightness. The top of the portion 1 is closed by a block 2 over which an ornamental cover plate 3 is positioned, and a partition 4 is positioned within the portion 1, adjacent the lower edge thereof.

The block 2 and plate 3 are perforated and through these perforations passes a metallic rod 5, the upper portion of which is attached thereto. The lower end of the rod is adapted to be received within the hollow portion 6 of a standard having a suitable base 7, and thumb screws 8 and 9 are adapted to bind the rod 5 at any desired elevation. A nut 10 is screwed upon the upper

portion of the rod 5 and on this nut the block 2 is adapted to seat, an ornamental knob 11 being thereafter screwed on the upper portion of the rod 5 for the purpose of preventing the inadvertent lifting of the bust portion and to serve as a handle when moving the form from place to place.

Secured to the lower edge of the bust portion 1, is the upper edge or sheath 12 which 10 constitutes the skirt portion of the form. The sheath 12 is provided at its lower edge with a hem 13 in which is housed an oval ring 14, which serves to impart the desired shape to the lower edge of the skirt. The 15 ring 14 is adapted to be properly centered with respect to the standard 6, by spacing arms 15, secured at opposite ends to the ring 14 and shaped intermediate their ends into semi-circular portions, adapted to collectively embrace the hollow portion 6 of the 20 standard.

When the construction is to be employed as a full length form, the members are associated in the manner described and as clearly 25 shown in Fig. 1, from which it will be seen that the form is carried in upright position by the standard which forms its support.

If it is now desired to use the form purely 30 as a bust form and support the same on a counter or otherwise than by the standard shown in Fig. 1, the knob 11 may be screwed off of the rod 5. Thereafter the skirt portion 12 may be collapsed within the hollow bust portion, and into the position shown in 35 Figure 2, the ring 14 being of such size as to wedge firmly within the bust portion and maintain the parts in this position. The bust portion, with the skirt portion in concealed position, may then be set upright on 40 a table or other form of support 16.

If it is desired to merely lower the bust 45 form without necessarily removing it from the standard, as for packing for shipment or storage, the thumb screws 8 and 9 may be simply loosened and the rod 5 allowed to drop, after the skirt portion has been collapsed, whereupon the parts will partake of the relative positions shown in dotted lines 50 in Figure 2. The thumb screw 9 may then be tightened to hold the parts in this posi-

tion and if desired the device may be lifted about by the knob 11.

Many advantages flow from the specific structure described, among which may be enumerated, economy of manufacture, sightliness, compactness for shipping and storing, lightness and durability.

I am aware that in articles of the general class under consideration, it has been common to associate with the bust portion a collapsible skirt portion composed of metallic parts, but in dismantling such articles it is necessary to draw the metallic parts upwardly over the bust portion, and this operation not infrequently results in tearing 65 the jersey or similar cloth forming the exterior of the bust portion.

It will be understood that changes may be made in the specific structure described, such as the substitution of equivalents, or by 70 using certain parts of the device instead of the entire structure, without departing from the spirit or substance of the invention, the scope of which is commensurate with the 75 appended claim:

Having thus fully described the invention, what I claim as new and desire to secure by Letters Patent is:

A combined bust and skirt form embodying a rigid permanently shaped bust portion 80 provided with an open bottom chamber at its base, a skirt portion permanently secured to the bust portion and adapted to normally hang therefrom; said skirt portion being a fabric whereby it may be raised and collapsed into concealed position within the chamber in the bust portion, and a distending member permanently attached to the lower edge of the skirt portion for maintaining said portion in proper shape when the skirt portion is lowered and adapted to be forced into the chamber in the bust portion when the skirt portion is collapsed with said chamber, for maintaining the skirt portion in collapsed position within the chamber of the bust portion when the skirt portion is raised.

In testimony whereof I have signed the foregoing specification.

MAX BRECKER
